MINERAL CLASSIFIER MACHINE

Clifton W. Livingston, Baguio, P. I.

Application January 25, 1938, Serial No. 186,903

6 Claims. (Cl. 209—157)

The invention relates to a classifier and more especially to a mineral sorting or classifying apparatus for the mining industry.

The primary object of the invention is the provision of an apparatus of this character, wherein the deflection of particles or solid materials of various settling velocities when dropping the same into a horizontal current of liquid enables through the rise in such current the lifting of particles accordingly to their settling velocity, viscosity, size and shape and in this manner classifying of such material takes place for the assortment thereof.

Another object of the invention is the provision of an apparatus of this character, wherein separation of solids from liquids or separation between particles within the liquids having different settling velocity will be assured through the arrangement of a variable velocity horizontal current which is continuously active, non-pulsating and devoid of short circuiting thus in this manner the materials will be classified or separated for their assortment.

A further object of the invention is the provision of an apparatus of this character, wherein a part of the material stream is permitted to return behind an impeller and in this manner forming a complete circuit for classifying purposes and the operation being continuous, the remaining part of the stream being passed into overflow areas for further classification.

A still further object of the invention is the provision of a machine of this character, which is simple in its construction, thoroughly reliable and efficient in operation, novel in its make-up, mechanical in the working thereof, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a top plan view partly broken away of the apparatus constructed in accordance with the invention.

Figure 2 is a side elevation thereof.

Figure 3 is a sectional view taken on the line 3—3 of Figure 1 looking in the direction of the arrows.

Figure 4 is an end elevation.

Figure 5 is a sectional view taken on the line

5—5 of Figure 1 looking in the direction of the arrows.

Figure 6 is a sectional view taken on the line 6—6 of Figure 1 looking in the direction of the arrows.

Figure 7 is an enlarged fragmentary vertical sectional view through one of the stuffing boxes employed in the machine.

Similar reference characters indicate corresponding parts throughout the several views in the drawings.

Referring to the drawings in detail, the apparatus comprises a tank 10 provided with a sloping bottom 11 permanently closed and reinforced by longitudinal and transverse sills 12 and 13, respectively, these being exteriorly of the tank while the top of such tank is open and the major longitudinal extent of this open top lays in a horizontal plane as at 14 while the remaining minor portion of said open top is elevated 15 and inclined longitudinally toward the horizontal portion 14 with the bottom 11 coextensive with this remaining portion 15. In this construction of the tank there is created interiorly thereof a relatively deep end and a shallow end, respectively, while the bottom 11 in its inclined disposition is supported upon columns or uprights 16 and 17, respectively, which are suitably anchored to a foundation and are made fast to the said bottom 11 in any suitable manner. The deep end of the tank 10 is at rest upon the foundation from which rise perpendicularly the columns or uprights 16 and 17. Disposed at opposite ends of the tank 10 are suitable bearings 18 in which are journaled horizontal axles 19 disposed crosswise with respect to the open top of the tank 10 while low within the deep end of said tank is a horizontally arranged axle 20 being disposed transversely of said tank and these axles 19 and 20 are fitted with sprocket wheels 21 and 22, respectively, over which are trained the sprocket chains 23 of an endless movable conveyor having spaced flights 24 lying crosswise of the said conveyor and serving as drags for such conveyor. The axle 20 is disposed in vertical alignment with the axle 19 arranged at the deep end of the tank 10 so that the chains 23 of the conveyor will have travel in a perpendicular direction effecting a perpendicular stretch A to said conveyor while another stretch B of the said conveyor follows the incline or angular disposition of the bottom 11 of the said tank. The axle 19 arranged at the higher end of the tank 10 has fixed thereto a belt wheel 25 over which is trained an endless belt 26 engaged about

a driving pulley 27 in association with a speed reducing mechanism (not shown) and confined within a housing 28 stationarily carried on a stand, slab or block 29 and such mechanism is connected with a power unit 30, in this instance an electric motor, which is also carried by the slab or block 29. Thus the unit 30 operates the conveyor with the flights 24 thereon for a purpose presently described.

10 Within the tank 10 are vertically arranged spaced transversely disposed partitions 31, these at the upper ends are inset from the open top of the tank while the lower ends of said partitions are removed from the stretch B of the 15 flight conveyor and divide the deep end of the tank into sorting zones 32 and 33 and a washing and sorting column 34, respectively, the said column being intermediate of the zones 32 and 33. Within the column 34 next to one side of the 20 tank 10 is a laterally inwardly inclined deflector plate 34 which is disposed above spaced transversely arranged inverted substantially V-shaped angular irons 36, these being fixedly supported at opposite sides of the tank 10 and are preferably elevated with respect to the stretch B of the 25 flight conveyor. Built in the side of the tank 10 directly opposite the deflector plate 35 is a funnel 37 having a flared mouth 38 next to the plate 35, being open at opposite ends and tapers 30 reversely to the mouth 38 while within the smaller end of this funnel 37 is a bladed propeller 39, its driving shaft 40 is carried through a liquid stuffing box 41 to without the tank 10 where it has fitted thereto a belt pulley 42 over which is 35 trained an endless belt 43 about a driving pulley 44 in association with speed reducing mechanism (not shown) and contained within a housing 45, the said mechanism being operatively connected with a power unit 46, in this instance an electric motor carried upon a stand, slab or 40 block 47, the housing 45 being also supported by the latter. The funnel 37 within its mouth 38 has arranged therein eddy reducing screens 48. The propeller 39 when active produces a 45 horizontal current to liquid within the tank 10 at the deep end thereof while the screens 48 are designed to reduce eddy currents and effect streamlined motion to the liquid of diluting characteristic.

Above the funnel 37 and carried laterally into 50 the tank 10 through the open top of the same is a feed launder 49 having a downwardly elbowed inner end forming a feed discharge spout 50 directing material in a downward direction crosswise of the horizontal current set up by the 55 funnel 37 within the washing and sorting column 34 and this unclassified material fed as stated will be subjected to a lifting activity resultant from a rising current of liquid present within the tank 10, the ability of the said rising 60 current to lift particles or solid matter depends upon the settling velocity, mass, size and shape of the particles as well as the velocity of the rising current and the density and viscosity of the medium. Those particles whose settling velocities in a medium of any given density are greater than the velocity exerted by the rising 65 current of liquid will not be lifted by the current and are settled out of the same. Conversely, those particles whose settling velocities in a medium of any given density, are less than the 70 velocity of the rising current will be lifted by the current and in this manner sorting of the material takes place.

75 Arranged within the spout 50 in the path of

the feed of material in the launder 49 is a horizontal baffle 51 which functions to split the material into two independent flows or streams before the material falls into the advance horizontal current created by the propeller 39 expediting the sorting and washing activities within the column 34 when the apparatus is in operation.

Bordering the straight horizontal major portion 14 of the open top of the tank and transversely thereof are the intercommunicating side and cross overflow launders 52 and 53, respectively, which are common to and are superposed with respect to the zone 33 for coactivity with rising current areas denoted at a, b and c, respectively, the zone 33 being effective as a quiescent sorting zone in the operation of the apparatus. These overflow launders 52 and 53, the former being longitudinally of the tank and the latter disposed crosswise thereof, are equipped with adjustable weirs 54 for regulating under adjustment the overflow resultant from the rising currents in the areas a, b and c into the launders in the working of the machine. The launders 52 and 53 at their bottoms incline in one direction to effect a circuitous overflow leading into a discharge font 55 at the deeper end of the tank 10 and exteriorly of the latter. The font 55 has a pulp overflow discharge 56.

The deeper end of the tank 10 is equipped with a drain outlet 57 while the flight conveyor 24 is adapted in its travel through the flights 24 thereof to drag sand deposits upon the inclined bottom 12 of the tank 10 upwardly of said bottom and discharge such sand or the like through an outlet 58 at the elevated open top of said tank.

It is desirable that the axles 19 and 20 fit in liquid stuffing boxes 59, each having liquid stored therein through a supply conduit 60 from any suitable source of supply.

Heading the column 34 above the upper ends of the partitions 31 creating the same are baffles 61 under which the pulp stream flows into the rising current areas a adjacent thereto and such pulp is there free to overflow the weirs 54 into the launders 52 and 53 for the passage into the font 55, washing and settling activities being set up in the zones 32 and 33 and column 34, respectively, while quiet settling occurs in the zone 33.

In the working of the apparatus the mineral material is fed through the launder 49 discharging at 50 into a horizontal current of liquid impelled by the propeller 39, the flight conveyor removes the sand from the admitted material dragging it up the inclined bottom 11 for the discharge of the same at 58 from the tank at the elevated end thereof while the washing and sorting column 34 within the tank changes the horizontal current of liquid to a rising current, the baffles 61 being for the purpose of preventing short circuiting of the overflow and divides the current, one portion being returned behind the propeller 39 and the other portion passes into the overflow rising current areas a, b and c, respectively, the overflow being controlled through adjustment of the weirs 54 and such overflow is conveyed to the font 55 and has discharge at 56 therefrom. In the foregoing manner the solid matter will be sorted from the liquid or the particles separated from each other within the said liquid having different masses or settling velocities and in this fashion the apparatus functions as a classifier for mineral material.

What is claimed is:

1. A machine of the kind described comprising a tank open at its top and varying in depth in a

longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel and inclined in the direction thereof, baffles within said funnel and at the discharge side thereof, baffles working within the funnel for sending fluid in the direction of the baffles.

2. A machine of the kind described comprising a tank open at its top and varying in depth in a longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel and inclined in the direction thereof, baffles within said funnel and at the discharge side thereof, a propeller working within the funnel for sending fluid in the direction of the baffles, and intercommunicating side and cross overflow launders common to and superposed with respect to one of the said zones for coactivity with rising current areas within another of said zones.

3. A machine of the kind described comprising a tank open at its top and varying in depth in a longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel and inclined in the direction thereof, baffles within said funnel and at the discharge side thereof, a propeller working within the funnel for sending fluid in the direction of the baffles, inter-

communicating side and cross overflow launders common to and superposed with respect to one of the said zones for coactivity with rising current areas within another of said zones, and adjustable weirs within the said launders.

4. A machine of the kind described comprising a tank open at its top and varying in depth in a longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel and inclined in the direction thereof, baffles within said funnel and at the discharge side thereof, a propeller working within the funnel for sending fluid in the direction of the baffles, intercommunicating side and cross overflow launders common to and superposed with respect to one of the said zones for coactivity with rising current areas within another of said zones, and adjustable weirs within the said launders, the said launders at their bottoms being inclined in one direction to effect a circuitous overflow leading to a discharge at the deeper area of said tank.

5. A machine of the kind described comprising a tank open at its top and varying in depth in a longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel and inclined in the direction thereof, baffles within said funnel and at the discharge side thereof, a propeller working within the funnel for sending fluid in the direction of the baffles, intercommunicating side and cross overflow launders common to and superposed with respect to one of the said zones for coactivity with rising current areas within another of said zones, adjustable weirs within the said launders, the said launders at their bottoms being inclined in one direction to effect a circuitous overflow leading to a discharge at the deeper area of said tank, and horizontal baffles in the path of the feed from the feed launder for splitting material into two independent streams in advance of being subjected to current blast from said funnel.

6. A machine of the kind described comprising a tank open at its top and varying in depth in a

longitudinal direction from one end to the other thereof, vertical walls disposed transversely of the tank, spaced from the bottom and extending only to the liquid level for partitioning the deeper portion of said tank and dividing it into a plurality of sorting and washing zones, one of the partitions being arranged for effecting a vertical columnar sorting area, a conveyor working within the tank and having a vertical stretch within one sorting zone and an inclined stretch corresponding to the variation in depth of said tank, a feed launder having a downwardly elbowed inner end forming a discharge spout for directing material downwardly in said sorting columnar area, a funnel carried laterally into the tank below the launder and confronting the downward feed of the elbowed inner end of said launder, a deflector within the columnar area in the path of said funnel

nel and inclined in the direction thereof, baffles within said funnel and at the discharge side thereof, a propeller working within the funnel for sending fluid in the direction of the baffles, intercommunicating side and cross overflow launders common to and superposed with respect to one of the said zones for coactivity with rising current areas within another of said zones, adjustable weirs within the said launders, the said launders at their bottoms being inclined in one direction to effect a circuitous overflow leading to a discharge at the deeper area of said tank, horizontal baffles in the path of the feed from the feed launder for splitting material into two independent streams in advance of being subjected to current blast from said funnel, and flights built with the conveyor.

CLIFTON W. LIVINGSTON.
